HIGH VOLTAGE CAPACITOR DISCHARGE GROUNDING RELAY

Jack S. Hawkins, San Jose, Calif., assignor to Jennings
Radio Manufacturing Corporation, San Jose, Calif., a
corporation of Delaware

Filed Apr. 30, 1963, Ser. No. 74,679

Term of patent 14 years

(Cl. D26—10)

FIG. 1 is a side elevational view of a high voltage capacitor discharge grounding relay, showing my new design, the appearance from all sides being substantially the same;

FIG. 2 is a top plan view; and

FIG. 3 is a bottom plan view thereof.

I claim:

The ornamental design for a high voltage capacitor discharge grounding relay, as shown and described.
